[57] CLAIM

The ornamental design for a chessboard, as shown and described.

DESCRIPTION

FIG. 1 is a perspective view of the first embodiment of a chessboard embodying my new design;
FIG. 2 is a plan view of the chessboard of FIG. 1, the underside of the chessboard being planar;
FIG. 3 is a side view of the chessboard of FIG. 2 seen from the right side of FIG. 2;
FIG. 4 is a side view of the chessboard of FIG. 2 seen from the left side thereof;
FIG. 5 is a side view of the chessboard of FIG. 2 seen from the top side thereof;
FIG. 6 is a side view of the chessboard of FIG. 2 seen from the bottom side thereof;
FIG. 7 is a perspective view of another embodiment of a chessboard embodying the design;
FIG. 8 is a plan view of the chessboard of FIG. 7, the underside of the chessboard being planar;
FIG. 9 is a side view of the chessboard of FIG. 8 seen from the right side of FIG. 8.

FIG. 10 is a side view of the chessboard of FIG. 8 seen from the left side thereof;

FIG. 11 is a side view of the chessboard of FIG. 8 seen from the top side thereof;

FIG. 12 is a side view of the chessboard of FIG. 8 seen from the bottom side thereof;

FIG. 13 is a perspective view of another embodiment of a chessboard embodying the design;

FIG. 14 is a plan view of the chessboard of FIG. 13, the underside of the chessboard being planar;

FIG. 15 is a side view of the chessboard of FIG. 14 seen from the right side of FIG. 14;

FIG. 16 is a side view of the chessboard of FIG. 14 seen from the left side thereof;

FIG. 17 is a side view of the chessboard of FIG. 14 seen from the top side thereof;

FIG. 18 is a side view of the chessboard of FIG. 14 seen from the bottom side thereof;

FIG. 19 is a perspective view of another embodiment of a chessboard embodying the design;

FIG. 20 is a plan view of the chessboard of FIG. 19, the underside of the chessboard being planar;

FIG. 21 is a side view of the chessboard of FIG. 20 seen from the right side of FIG. 20;

FIG. 22 is a side view of the chessboard of FIG. 20 seen from the left side thereof;

FIG. 23 is a side view of the chessboard of FIG. 20 seen from the top side thereof;

FIG. 24 is a side view of the chessboard of FIG. 20 seen from the bottom side thereof;

FIG. 25 is a perspective view of another embodiment of a chessboard embodying the design;

FIG. 26 is a plan view of the chessboard of FIG. 25, the underside of the chessboard being planar;

FIG. 27 is a side view of the chessboard of FIG. 26 seen from the right side of FIG. 26;

FIG. 28 is a side view of the chessboard of FIG. 26 seen from the left side thereof;

FIG. 29 is a side view of the chessboard of FIG. 26 seen from the top side thereof;

FIG. 30 is a side view of the chessboard of FIG. 26 seen from the bottom side thereof;

FIG. 31 is a perspective view of a further chessboard embodying the design;

FIG. 32 is a plan view of the chessboard of FIG. 31, the underside of the chessboard being planar;

FIG. 33 is a side view of the chessboard of FIG. 32 seen from the right of FIG. 32;
FIG. 34 is a side view of the chessboard of FIG. 32 from the left side thereof;

FIG. 35 is a side view of the chessboard of FIG. 32 seen from the top side thereof;
FIG. 36 is a side view of the chessboard of FIG. 32 seen from the bottom side thereof.
